UNITED STATES PATENT OFFICE.

HOWARD TAYLOR BUCK, OF CEDAR KNOLLS, NEW JERSEY, ASSIGNOR TO T. S. BUCK
MFG. CO., OF NEW YORK, N. Y., A CORPORATION OF NEW YORK.

SIGNATURE STAMP FOR MULTIGRAPHING MACHINES.

Application filed December 26, 1924. Serial No. 758,219.

To all whom it may concern:

Be it known that I, HOWARD T. BUCK, a citizen of the United States of America, and a resident of Cedar Knolls, in the county of Morris and State of New Jersey, have invented a new and Improved Signature Stamp for Multigraphing Machines, of which the following is a full, clear, and exact description.

10 This invention relates to signature stamps for applying signatures to form letters and has particular reference to a signature stamp for use in connection with multigraphing machines.

15 Originally the signature stamps for use in connection with multigraph machines were produced by the electrotyping process so that the raised signature formed an integral part of a rigid metal backing plate. It 20 developed that the rigid metal type and backing plate tended to create a depression in the sheets which failed to closely simulate a written signature. The signature stamps were subsequently made from rubber or 25 other analogous materials which were elastic or yieldable but which were secured to a rigid backing member or base. These backing members or bases due to their rigidity, while of a fairly satisfactory nature have 30 been found to present certain difficulties on account of the slight variance of the diameter of the drums or rollers of the multigraphing machines to which they are applied.

35 It is therefore an outstanding object of the present invention to further improve the signature stamp whereby to eliminate this difficulty by providing the rubber signature sheet with a flexible, elastic and 40 conformable backing member or base thereby compensating for the variance in the diameter of the drums or rollers.

The invention furthermore comprehends a backing member or base of a flexible, elastic and conformable material which when flexed will not remain distorted.

45 The invention furthermore contemplates a signature stamp structure for multigraphing machines which is comparatively simple in its construction, inexpensive to manufacture and which is highly efficient in its purpose.

50 With the above recited and other objects in view, the invention resides in the novel 55 construction set forth in the following speci-

fication, particularly pointed out in the appended claim and illustrated in the accompanying drawings it being understood that the right is reserved to embodiments other than those actually illustrated herein, to the full extent indicated by the general meaning of the terms in which the claim is expressed.

In the drawings—

Figure 1 is a face view of a signature stamp constructed in accordance with the invention.

Fig. 2 is a transverse sectional view therethrough taken approximately on the line 2—2 of Fig. 1.

Referring to the drawings by characters of reference the signature stamp includes a strip 10 of yieldable material such as rubber or the like upon the face of which the raised or embossed signature 11 is produced. The 75 said strip is applied to a backing 12 by an adhesive layer or coating 13 such as shellac, ether, celluloid cement or any other suitable substance. The backing 12 is constructed of a material which is flexible and 80 elastic and which is generally of arcuate shape to fit the surface of the drums or rollers of a multigraph machine. By constructing the backing member or base 12 of a flexible or elastic material it is obvious that 85 the same is rendered conformable to the curvature of the drums or rollers and is therefore capable of compensating for variations in the diameter of the same. In using the 90 term elastic it is used in its broadest interpretation namely to imply that the same is capable of returning to a normal shape when flexed therefrom. The material from which the backing member or base 12 is formed is 95 preferably celluloid or a material having the characteristics of celluloid so that the same is not readily distorted by bending to a distorted position and which further includes the property of lightness.

I claim:

As a new article of manufacture a signature stamp for multigraphing machines comprising a strip of yieldable material having the signature raised thereon, a backing member or base constructed of celluloid and adhesively attached to said yieldable strip, said base being of arcuate formation with the yieldable strip attached to the convex surface thereof.

HOWARD TAYLOR BUCK.
